UNITED STATES PATENT OFFICE.

ALPHEUS FAY, OF LOUISVILLE, KENTUCKY.

VULCANIZER.

1,257,594.

Specification of Letters Patent. Patented Feb. 26, 1918.

Application filed June 25, 1917. Serial No. 176,769.

To all whom it may concern:

Be it known that I, ALPHEUS FAY, a citizen of the United States, residing at Louisville, in the county of Jefferson and State of Kentucky, have invented certain new and useful Improvements in Vulcanizers, of which the following is a specification.

My invention relates to portable vulcanizing apparatus for application of patches to the inner tubes of pneumatic tires or to similar articles which may be patched in such manner.

The object of my invention is to provide for more effective and rapid heating of the patch, thereby economizing in time and in the combustible used, as well as performing the vulcanizing operation more effectively and thus producing a somewhat better attachment of the patch.

A further object of my invention is to simplify the construction of apparatus of this character.

In the drawing:

Figure 1 is a general perspective view of a device embodying my invention and showing part of a tire with a patch being applied thereto;

Fig. 2 is a vertical cross section on a plane corresponding to the line 2—2 of Fig. 1;

Fig. 3 is a detail perspective view of the yoke and part of the screw;

Fig. 4 is a similar view of the conducting element;

Fig. 5 is a similar view of the combustible;

Fig. 6 is a similar view of a modified combustible;

Fig. 7 is a general perspective view similar to Fig. 1 of a device embodying a modification of my invention;

Fig. 8 is a partial perspective view showing a modification of the device shown in Fig. 7;

Fig. 9 is a vertical cross section on a plane corresponding to the line 9—9 of Fig. 7; and

Fig. 10 is a detail perspective view of the pan or conducting element of the device shown in Figs. 7 and 9.

As shown in Figs. 1 to 6, there is an elongated base-plate 1, preferably made of heavy sheet metal, wider at its middle than at its ends; and having integral with it at its ends, upturned standards 2 with transverse slots 3 through them in their upper end parts.

The beam 4 is preferably simply an elongated piece of metal of substantially rectangular cross-section with its ends lying in

the respective slots 3 and having a tapped hole 5 down through its middle through which is screwed a thumb-screw 6.

The yoke 7 is an elongated inverted shallow cup with rounded ends and with portions of what would be the bottom of the cup cut away adjacent to the ends and from there some distance toward the middle, so that openings 8 are left in the top of the yoke with a middle part 9 lying between them and having an opening 10 down through it. Also, preferably, some of the metal from each opening 8 is turned up next to the part 9, leaving transverse ribs 11 that strengthen this transverse part 9.

The thumb-screw 6 has its lower end part 12 reduced in diameter which passes through and fits loosely in the opening 10 and leaves a shoulder 13 bearing down on the upper side of the part 9 around the opening 10. The lower end 14 of this part 12 is spread out under the lower side of the part 9 around the opening 10 like the head of a rivet, but not tightly. Thus, the yoke 7 is held on the lower end part of the thumb-screw 6 but may turn freely thereon or permit free turning of the thumb-screw while the yoke remains stationary.

The conducting element 15 is of elongated round-ended formation corresponding to that of the yoke 7, and preferably has a slightly upturned inclined or conical flange 16 all around it to strengthen it adjacent to its edges, as well as to conveniently guide said yoke 7 in the proper location relative to the conducting element; the flange 16 fitting all around the outside of the lower edge part of the yoke 7, as shown in Figs. 1 and 2.

The combustible 17 is preferably a piece of pasteboard or similar absorbent material impregnated with a suitable inflammable substance which may be of any one of a number of various compositions suitable for this purpose, and which, being well known, need not be more specifically described herein. This piece of material is made of suitable size and shape to fit up inside the inverted cup-shaped yoke 7, as is best seen in Fig. 2, being held therein by frictional contact of parts of its edges with the inner sides of the yoke.

With the parts thus provided, the tube 18 is laid out flat on the upper side of the base-plate 1 and the patch 19 is laid in the desired position on the tube, as shown in Fig. 1. While this is being done, the beam

4 with the screw 6 and yoke 7 hanging thereon is preferably out of its position in the slots 3, leaving free access to the open bottom of the inverted cup-shaped yoke 7. 5 Thus, the combustible 17 may be inserted up in the yoke 7 and ignited on its lower side. Then the beam 4 may be quickly placed in position in the slots 3 and a few turns of the thumb-screw 6 are sufficient to clamp the 10 yoke 7 down tightly against the conducting element 15, binding the patch 19 to the tube 18 all around the edges of the patch. The combustible 17 being suspended up in the yoke 7 and not resting directly on the upper 15 surface of the conducting element 15 is thus enabled to burn on its lower side and the combustion is thus directly adjacent to the upper side of the conducting element 15 and able to act most effectively from the very 20 beginning of the operation after the parts have been clamped together.

To facilitate this combustion on the lower side rather than on the upper side of the combustible as in other vulcanizers, I prefer to provide the combustible 17 with 25 perforations 20 at intervals in its interior, and also preferably provide its edge all around with serrations 21, as is best seen in Fig. 5. Or as it is shown in Fig. 6, the 30 combustible 17' may have only the perforations 20 without the serrations; or it will be understood that the perforations 20 might be omitted from the combustible in Fig. 5. To further facilitate this combustion down 35 between the main body of the combustible and the conducting element 15, I prefer to provide the lower edge or rim of the yoke 7 with notches 22 at intervals throughout its extent, so that the yoke has a sufficiently 40 nearly continuous bearing throughout its length on the conducting element 15 to avoid any buckling or uneven pressure of the conducting element on the edge parts of the patch 19.

45 Thus, if the combustible 17 is provided with the openings 20 or the serrations 21, or both, there are spaces for inlet or outlet of air past the main body of combustible into the space 23 therebelow next to the conducting element 15 where the combustion is to occur; while the notches 22 permit air to pass the lower part of the yoke 7 into this space. In fact, with lateral openings such as the notches 22 in conjunction with either 50 the perforations 20 or the serrations 21, a substantial draft of air is permitted through the space 23, so that the combustion may be much more thorough and rapid and much hotter than that which takes place on the 55 upper part of the body of combustible in such apparatus.

In the modification shown in Fig. 7, the elongated base-plate 1' resembles that in the previous example except that its upturned 60 integral standards 2' at its ends, instead of

having transverse slots have their upper end parts turned down horizontally toward each other across the main part of the base-plate, thus forming ears 3' under which the beam 4 is slid horizontally to bring the parts into 70 clamping condition.

In the further modification shown in Fig. 8, it will be understood that the base-plate is of the construction shown in Fig. 7 but the beam 4' is pivoted to one of the ears 3' 75 by a rivet 24 passing vertically through the ear at the end part of the beam that lies under the ear. Thus, the beam 4 may be swung in a horizontal plane around to one side of the device carrying the screw 6 therewith with the yoke hanging on the screw.

Another modification illustrated in Figs. 7 and 9 is in that the yoke 7' is not of inverted cup-shaped formation but is merely a flat member corresponding to the bottom of the 85 inverted cup or top of the yoke 7 of the previous example. Instead of the conducting element 15 with the relatively low flange 16 around it, there is provided in conjunction with this modified yoke a pan or modified conducting element 25 of considerable depth with its side walls inclined outward all around and provided with openings 26 at intervals around said side walls. The combustible 17' may be in every respect 95 similar to the combustible 17 of the previous example, so long as it is of such extent that it will rest on the inner sides of the pan walls at such a height that its lower surface is raised considerably above the bottom of the pan, leaving a space 23' with which the openings 26 communicate. The yoke 7' bears on the rim 27 of the pan 25 which is preferably flanged outward to leave a broad bearing surface for the flat lower 105 side of the yoke 7.

It will be seen that the operation of this modification is like that of the previous example, the chief difference being that as the yoke 7' does not hold the combustible 17' 110 for access to the bottom thereof, the ignition of the lower side of the combustible is somewhat less convenient; although there is an added convenience in not having to lift the beam 4 with the yoke 7' suspended thereon for this access to the bottom of the combustible. Therefore, this modification of the arrangement of the combustible is well adapted in conjunction with the swinging beam of Fig. 8.

It will be understood, however, that the modified arrangement of combustible and the modified arrangement of the base-plate and beam of either Fig. 7 or Fig. 8 are not peculiar to each other; since the base plate 125 and beam of either Fig. 7 or Fig. 8 may be used in conjunction with the arrangement of combustible shown in Figs. 1 to 6, or the base-plate of Figs. 1 to 6 may be employed as part of the clamping means in conjunc- 130

tion with the arrangement of combustible shown in Figs. 7 and 9.

It will be seen that after the combustible 17' has been ignited and placed in the pan 5 25 with its ignited side downward there will be free access of air through the openings 26 to the space 23' and free exit of air through the openings 20' in the combustible 17' and out through the openings 8' of the 10 yoke 7'. Thus, the principle of operation of this modification is the same as that of the previous example. It will be understood that the combustible may have either the 15 perforations 20' or serrations 21', or both, as shown in the drawing.

It will be seen that with any of these examples, not only does the combustion occur immediately adjacent to the thin conducting element 15 or 25 that rests directly on 20 the patch 19, but this combustion is adapted to be somewhat hotter because the air is admitted below the burning combustible. With my invention involving a suspended 25 combustible there is practically no insulation of the burning part of the combustible from the heated conducting element 15 or 25 that is pressed directly against the upper side of the patch 19.

The extremely simple construction comprising the base-plate 1' with its integral standards 2 or 2' and the beam 4 receiving the screw 6 is preferred where economy of material and labor in the construction of the device is highly desirable; as well as to 30 afford a device more durable and less liable to derangement than many of the more complicated devices now in use. However, it will be understood that my invention is susceptible to some modification to adapt it to 35 various requirements which may be encountered, and therefore, I do not wish to be understood as being limited to the precise details of construction and operation herein set forth as examples, but having thus fully 40 45 exemplified my invention, what I claim as new and desire to secure by Letters Patent is:

1. In a vulcanizer, in combination with a support for the article to be vulcanized, and 50 means to be clamped against the parts to be vulcanized and heated while so clamped, means to clamp said means to be heated, and means for supporting a combustible in suspended condition whereby it is adapted to 55 burn on its lower side immediately adjacent to said means to be heated.

2. In a vulcanizer, in combination with a support for the article to be vulcanized, and means to be clamped against the parts to be 60 vulcanized and heated while so clamped, means to clamp said means to be heated, and means for supporting a combustible in suspended condition whereby it is adapted to 65 burn on its lower side immediately adjacent to said means to be heated, said clamping

means having an opening in its top, and said means so supporting said combustible that there is a space for air to pass said combustible to or from the lower side thereof adjacent to said means to be heated.

3. In a vulcanizer, in combination with a support for the article to be vulcanized, and means to be clamped against the parts to be vulcanized and heated while so clamped, and a clamping member bearing on said means 70 to be heated and having an open bottom to hold a combustible suspended in said open bottom whereby it is adapted to burn on its lower side immediately adjacent to said means to be heated.

4. In a vulcanizer, in combination with a support for the article to be vulcanized, and means to be clamped against the parts to be vulcanized and heated while so clamped, and a clamping member bearing on said means to 80 be heated and having an open bottom to hold a combustible suspended in said open bottom whereby it is adapted to burn on its lower side immediately adjacent to said means to be heated, said clamping means 85 having an opening in its top, and so supporting said combustible that there is a space for air to pass said combustible to or from the lower side thereof adjacent to said means to be heated.

5. In a vulcanizer, in combination with a support for the article to be vulcanized, and means to be clamped against the parts to be vulcanized and heated while so clamped, and a clamping member bearing on said 90 means to be heated and having an open bottom to hold a combustible suspended in said open bottom whereby it is adapted to burn on its lower side immediately adjacent to said means to be heated, said clamping means 95 having an opening in its top, and so supporting said combustible that there is a space for air to pass said combustible to or from the lower side thereof adjacent to said means to be heated.

6. In a vulcanizer, in combination with 100 means to be clamped against the parts to be vulcanized and heated while so clamped, clamping means comprising a single elongated flat piece of metal of substantially uniform thickness throughout with a middle 105 major flat part to form a base plate, and integral upturned parts at its opposite ends to form standards, each of said standards having near its upper end transverse engaging means, an elongated beam with its end parts 110 adapted to be inserted under or withdrawn from under said engaging means, and means 115 to coact with said beam and clamp said parts to be vulcanized when said beam is inserted under said engaging means.

7. In a vulcanizer, in combination with a support for the article to be vulcanized, a thin sheet-metal conducting element to bear on the part to be vulcanized, and a yoke having an open bottom with a rim bearing on said conducting element to hold a combustible up in the inside of said yoke by a frictional contact of edge parts of said combustible with inner side parts of said yoke, and means to clamp said yoke down against said conducting element.

8. In a vulcanizer, in combination with a support for the article to be vulcanized, a thin sheet-metal conducting element to bear on the part to be vulcanized, and a yoke having an open bottom with a rim bearing on said conducting element to hold a combustible up in the inside of said yoke by frictional contact of edge parts of said combustible with inner side parts of said yoke, said conducting element having an upturned conical flange around it whereby said yoke is guided into proper relative position on said conducting element, and separable means for clamping said yoke against said conducting element.

9. In a vulcanizer, in combination with means to be clamped against the parts to be vulcanized and heated while so clamped, clamping means comprising a single elongated flat piece of metal of substantially uniform thickness throughout with a middle major flat part to form a base plate, and integral upturned parts at its opposite ends to form standards, each of said standards having near its upper end transverse engaging means, an elongated beam with its end parts adapted to be inserted under or withdrawn from under said engaging means, a screw threaded through the middle part of said beam, and an open-bottomed yoke swiveled on the lower end part of said screw and adapted to clamp said means against said part under the pressure of said screw when said beam is held in said slots.

10. In a vulcanizer, in combination with means to be clamped against the parts to be vulcanized and heated while so clamped, clamping means comprising a flat elongated base-plate having integral upturned standards at opposite ends, each of said standards having transverse engaging means, an elongated beam of substantially rectangular cross-section with its end parts adapted to be inserted in or withdrawn from under said engaging means, a screw threaded through the middle part of said beam, and an open-bottomed yoke swiveled on the lower end part of said screw and adapted to clamp said means against said part under the pressure of said screw when said beam is held in said slots.

gated beam of substantially rectangular cross-section with its end parts adapted to be inserted under or withdrawn from under said engaging means, a screw threaded through the middle part of said beam, and an open-bottomed yoke swiveled on the lower end part of said screw and adapted to clamp said means against said parts under the pressure of said screw when said beam is held under said engaging means, and to support a combustible whereby it is adapted to burn on its lower side immediately adjacent to said means to be heated.

11. In a vulcanizer, in combination with means to be clamped against the parts to be vulcanized and heated while so clamped, clamping means comprising a flat elongated base-plate having integral upturned standards at opposite ends, each of said standards having a transverse slot, an elongated beam of substantially rectangular cross-section with its end parts adapted to be inserted in or withdrawn from said slots, a screw threaded through the middle part of said beam, and an open-bottomed yoke swiveled on the lower end part of said screw and adapted to clamp said means against said parts under the pressure of said screw when said beam is held in said slot.

12. In a vulcanizer, in combination with means to be clamped against the parts to be vulcanized and heated while so clamped, clamping means comprising a flat elongated base-plate having integral upturned standards at opposite ends, each of said standards having a transverse slot, an elongated beam of substantially rectangular cross-section with its end parts adapted to be inserted in or withdrawn from said slots, a screw threaded through the middle part of said beam, and an open-bottomed yoke swiveled on the lower end part of said screw and adapted to clamp said means against said parts under the pressure of said screw when said beam is held in said slots, and to hold a combustible whereby it is adapted to burn on its lower side immediately adjacent to said means to be heated.
